JEWELRY CLASP

Jack Stern, New York, N. Y.

Application May 7, 1941, Serial No. 392,272

1 Claim. (Cl. 24—230)

This invention relates generally to improvements in jewelry clasps, but more particularly to a separable clasp used to connect articles of jewelry, including watches and medallions, to the ends of straps, clips, chains and flexible strings.

The main object of the invention resides in the construction of a separable clasp to disengageably connect articles of jewelry to the ends of straps, clips, chains and flexible strings so that any undue tension along the axis of the connected members will not result in the disengagement of the clasp. In the attachment between a wrist watch and the straps therefor, it is well known that the connecting joint becomes loose or disengaged when excessive tension is applied along the strap axis. This condition also exists between a pendant watch or other article of jewelry hanging from a chain, flexible string or clip member.

This invention contemplates a construction of a separable clasp wherein engagement and disengagement of its members take place, at an angle to the longitudinal axis of the joined pieces. In this manner of attachment, no amount of tension on the connected pieces along the axis of the joined pieces can disengage the connection.

A further object of the invention resides in the construction of a separable clasp wherein the socket member is permanently secured to the jewelry piece and forms an aesthetic joint with the cooperating spring or latch member secured at the end of the connecting piece, wherein the clasp is easy to operate, is simple in construction and economical to manufacture.

These objects and other incidental ends and advantages of the invention will hereinafter appear in the progress of the disclosure and as pointed out in the appended claim.

Accompanying this specification, is a drawing showing a preferred embodiment of the invention as applied to different articles of jewelry and to different types of supporting members therefor, wherein corresponding reference characters designate corresponding parts throughout the several views and wherein:

Figure 1 is a top plan view showing the separable clasp as applied to a wrist watch and to straps therefor.

Figure 2 is a front and enlarged view in elevation of a watch showing the clasp socket members secured to said watch and the cooperating spring or latch members in engaged and disengaged position with said socket members.

Figure 3 is an enlarged view in perspective of the spring member of the separable clasp.

Figure 4 is an enlarged view, partly in section, of Figure 2, taken along the plane 4—4 thereof.

Figure 5 is a front view in elevation of a pendant watch connected to a vertical member of a clip by means of the separable clasp.

Figure 6 is a front view in elevation of a medallion connected to a flexible string by means of the separable clasp.

In accordance with the invention and the preferred embodiments shown, numeral 10 indicates generally a wrist watch of any desirable shape having conventional parts such as a back *a*, a center *b*, a bezel 12 and a crystal *d*. A socket member having a bottom opening is adapted to be secured on opposite edges 13 of the watch case center whereby a cooperating spring or latch member is easily accessible to the opening of each socket member for engagement therewith.

In the watch shown, opposite and parallel lateral shoulders 11 are formed between edges 13 of center *b* and the raised convex lateral walls of bezel 12. A socket member having a bottom opening is adapted to be secured against each of the edges 13 of the center *b* and is comprised as shown of spaced front and rear walls 14 and 15 each with right-angle cutout for attachment to shoulder 11 and edge 13 intermediate the length. Connecting the said front and rear walls 14 and 15 is an outer wall 16 and an inner wall 17 joined by a curved upper wall 16a. A bottom opening 19 is thus formed on each socket, edge 13 of center *b* serving as the inner wall thereof as seen in Figure 4 of the drawing. Secured to wall 13 opposite the upper edge of outer wall 16 of the socket member is a cross bar 18 between the front and rear walls 14 and 15, the upper wall of said cross bar 18 serving as an engaging flange for a detent shoulder of a spring or latch member.

The spring or latch member of the clasp is best shown in Figure 3. Spring walls 20 and 21 are bent in the form of a V, wall 20 being folded outwardly and downwardly at the upper end as at 25 to form a hook or engaging means with wall 20 for the outer wall 16 of the socket member.

Wall 21 at the upper portion is reduced in thickness to provide a detent shoulder 22, the upper end of the reduced portion being curved outwardly as at 23. Intermediate the curved wall 23 is a finger engaging lug 24 for purposes of compressing the clasp for engagement and disengagement with the socket member. Detent shoulder 22 is adapted to engage the upper wall of cross-piece 18 for latching purposes.

A wrist watch strap 27, doubled on itself, is adapted to engage a ring 26 secured to the front

face of wall 25 of the spring member. Wrist watch strap 27 is provided with the usual securing ring 28 and terminates at its free ends in a clasp member 29 engageable by a conventional connecting member 30. It is, of course, understood that a chain having a link connected to ring 26 may be used instead of strap 27.

Figure 4 illustrates how the spring and the socket member of the separable clasp may be engaged and disengaged. Thus, the spring member engages the socket member at right angles to the axis of the watch strap, which latter engages ring 26. In order to disengage the spring member from the socket member, it is necessary to compress wall 21 by forcing lug 24 outwardly, thereby freeing the detent shoulder 22 from the upper wall of cross-piece 18. After such compression, the spring member is lowered out of the socket member. In order to form an engagement between the spring member and the socket member, the former is merely forced into the bottom opening 19 of the socket member until a click is heard indicating engagement between detent shoulder 22 and the upper wall of cross-piece 18.

In Figure 5 is shown a watch 10 having a socket member and spring member as described. A link 31 is secured to the front wall 25 of the spring member, the said link being connected with a bar 33 of a clip 34 by means of a link 32, the clip 34 having the usual securing pin 35 thereon. In Figure 6 is shown a medallion 10a instead of a

watch and is secured to a flexible cord 36 engaging a ring 37, the latter being connected to a link or ring 31 by means of link 32.

The separable clasp above described is thus made to operate at right angles to the axis of the connected article of jewelry to the supporting member therewith. The only way in which the separable clasp may become disengaged, is by compression of the spring member and downward pressure thereon at right angles to the axis of the supporting member such as a strap, flexible cord, chain or bar. Such means of engagement insures safety of connection between an article of jewelry and its supporting piece.

15 I wish it understood that minor changes and variations in the material, construction, location, integration and shape of parts may all be resorted to without departing from the spirit of the invention and scope of the appended claim.

20 I claim:

A separable clasp for a watch including an inverted socket member projecting from and secured to the edge of said watch and having an opening spaced above the back thereof, a resilient separable latching member having inverted V-shaped walls engageable within said socket and an upwardly turned outer wall engageable with and externally disposed of said socket member, the said outer wall being adapted to have secured thereto a connecting member.

JACK STERN.
